(57) **CLAIM**

The ornamental design for a bottle, as shown and described.

DESCRIPTION

FIG. 1 is a front perspective view of the bottle;
FIG. 2 is a front elevation view of the bottle;
FIG. 3 is a rear elevation view of the bottle;
FIG. 4 is a right side view of the bottle;
FIG. 5 is a left side view of the bottle;
FIG. 6 is a top view of the bottle;
FIG. 7 is a bottom view of the bottle;
FIG. 8 is an environmental perspective view including the
bottle;
FIG. 9 is an alternative front perspective view of the bottle;
FIG. 10 is a front perspective view of a second embodiment
of the bottle;
FIG. 11 is a front elevation view of a second embodiment of
the bottle;
FIG. 12 is a rear elevation view of a second embodiment of
the bottle;
FIG. 13 is a right side view of a second embodiment of the
bottle;
FIG. 14 is a left side view of a second embodiment of the
bottle;
FIG. 15 is a top view of a second embodiment of the bottle;
FIG. 16 is a bottom view of a second embodiment of the
bottle;
FIG. 17 is an environmental perspective view including a
second embodiment of the bottle; and,
FIG. 18 is an alternative front perspective view of a second
embodiment of the bottle.

The broken lines shown in the drawings represent portions
of the bottle or environment that form no part of the claimed
design.

1 Claim, 14 Drawing Sheets

Related U.S. Application Data

No. 15/951,054, filed on Apr. 11, 2018, now Pat. No. 10,793,815.
